ors to Landis Tool Company, Waynesboro, Pa.

Application July 7, 1944, Serial No. 543,780

3 Claims. (Cl. 51—103)

1

The invention relates to metal working machines and more particularly to an abrasive machine of the type used for grinding screw threads on work pieces.

The usual method of grinding a thread on a work piece is to mount the same on centers and subject it to the action of a grinding wheel having either a single or multiple grooved and ridged peripheral surface. The work is rotated and traversed past the grinding wheel in a manner similar to that of chasing threads on a lathe.

It is the purpose of this invention to provide a centerless grinding machine for grinding threads. Such a machine for grinding threads would make available for thread grinding all the advantages of the centerless grinding method.

So far as it is known, no one has ever offered to the general trade a practical and successful centerless thread grinder. Our invention provides a machine which has proven in actual use its ability to grind threads accurately, quickly and on a practical basis.

An object of the invention is to provide a centerless grinding machine which is so constructed as to form and shape threads on a work piece to a desired standard.

A further object of the invention is to provide a centerless grinder wherein the grinding wheel proper has parallel annular ridges with grooves therebetween which are shaped so as to form threads on a work piece to a desired standard.

A further object of the invention is to provide a centerless grinder of the above type wherein the work rest is tilted relative to the axis of the grinding wheel to an angle substantially corresponding to the helix angle of the thread to be formed on the work piece.

A further object of the invention is to provide a centerless grinder of the above type having a tilted work rest wherein the axis of the control wheel is tilted relative to the grinding wheel to an angle substantially corresponding to double the helix angle of the standard thread to be formed on the work piece.

A still further object of the invention is to provide a centerless grinder of the above type having annular ridges on the grinding wheel thereof with means for shaping said ridges so as to form and shape threads on the work piece to a desired standard.

These and other objects will in part be obvious and will in part be hereinafter more fully disclosed.

Figure 16 shows the path of the work relative to the grinding wheel.

Figure 17 shows the vertical position of the work piece at the beginning and at the end of the grinding operation.

Figure 18 is a partial plan view of a dressing mechanism for dressing the control wheel.

Figure 19 is a partial front view of a dressing mechanism for dressing the control wheel.

This invention comprises a bed having a work rest or other support mounted directly thereon, a grinding wheel unit movably mounted at one side of the work rest and a control wheel unit movably mounted at the other side of the work rest.

The invention has to do with a centerless grinder which is so constructed as to form or shape threads on a work piece to a desired standard. The machine, in the preferred form illustrated, includes a grinding wheel having annular ridges with grooves therebetween on the periphery thereof, which ridges and grooves are so shaped as to produce during the grinding operation threads on a work piece of a desired standard. Cooperating with this grinding wheel

55 is a control wheel which is spaced therefrom

so as to provide a throat for the work piece. Said control wheel is driven at a lower speed than the grinding wheel so as to cooperate with the grinding wheel in rotating and feeding the work piece. A work rest is placed between the grinding wheel and the control wheel on which the work is supported and moved during the grinding operation. This work support is stationary and has a smooth supporting surface so that the work piece may be moved freely thereon. The work rest is tilted at an angle to the axis of the grinding wheel so that the ridges on the grinding wheel will properly engage or form the threads on the work piece resting on the work support for the shaping of the threads to a desired standard. This angle of the work rest relative to the axis of the grinding wheel corresponds substantially to the helix angle of the thread. The axis of the control wheel is likewise inclined to the axis of the grinding wheel so that the feeding action on the work piece through contact of the control wheel therewith is a forward feed of the work piece at a rate which will permit the grinding wheel to grind evenly on both sides of a thread. This angle of the axis of the control wheel relative to the axis of the grinding wheel corresponds substantially to double the helix angle of the thread and feeds at the rate of one or more full thread per revolution of the work piece.

While the machine herein shown and described has the grinding wheel, control wheel, and work holder or work rest arrangement generally in a horizontal plane, it will be understood that these units could be equally well arranged in vertical relation or at any intermediate angle so that the work piece will rest entirely or to a varying degree upon the control wheel and the work holder will merely position the workpiece in proper relation in the grinding throat between the wheels.

Grinding wheel mounting.—Referring more in detail to the drawings, the bed of the machine is indicated at 10. The grinding wheel base 11 is slidably mounted thereon for movement toward and from a work piece indicated at 12. The grinding wheel unit includes a grinding wheel 15 rotatably mounted on said base 11. Said grinding wheel may be moved toward and from working position by means of a screw 20, rotatably mounted in said wheel support and engaging a nut 21 secured to said bed. Said screw may be rotated by means of hand wheel 25 acting thru a differential transmission not shown, a shaft 26 having a worm gear 27 thereon meshing with the teeth of a worm wheel 28 on said screw. Shafts 26 may be rotated either by means of hand wheel 25 or by a handle 29 in ring 31 which may be clamped to hand wheel 25 by means of a clamping bolt 30. The range of movement of handle 29 may be determined by any suitable arrangement of stop devices. The grinding wheel 15 is driven by a motor 140 on the wheel base.

The wheel base 11 may be tilted at a slight angle as shown in Figure 3. This has the effect of increasing the range of helix angles which may be accommodated on the machine.

A series of annular grooves 16 is formed between ridges 17 on the face of wheel 15. The form of these grooves is slightly different than the form of the thread to be ground since the thread of the work piece is a continuous helical curve and the line joining the corresponding points of contact between wheel and work on opposite faces of a thread is not parallel with the axis of the screw thread and differs in length

from a line joining corresponding points on opposite faces of a thread in a plane containing the axis of the screw. The length of this line and the angle of the groove may be determined by means of the disclosures in Figures 9 and 10 in which the line N—N which is parallel to the axis of the grinding wheel 15 is spaced angularly from the axis of the work by the helix angle. Considered in plan view, the angles ON₁X₁ and ON₂X₂ are right angles by construction. Therefore the lines OX₁ and OX₂ are the hypotenuses or long sides of the two triangles. The combined line X₁X₂ represents the width of the V of the thread on the work piece along a plane 15 thru its axis. The other two sides ON₁ and ON₂ are the short sides of the triangles and the combined line N₁N₂ represents the width of a groove on the grinding wheel and on the wheel forming tool. Hereafter reference will be made only to the ridges on the grinding wheel.

The angle at the apex of the ridges on wheel 15 as well as on crusher 113 may be determined by means of the diagram shown in Figure 9 in which:

25 Angles acb, oab, and oac are right angles.

Angle A—= $\frac{1}{2}$ angle at apex of thread

$$An = \frac{1}{2} \text{ angle at apex of ridge on wheel}$$

$$30 \quad \text{Tan } A = \frac{ab}{ao}$$

$$\text{Tan } An = \frac{ac}{ao}$$

$$35 \quad \text{Cos } B = \frac{ac}{ab}$$

where angle B is the helix angle

$$40 \quad \frac{ac}{ao} = \frac{ac}{ab} \times \frac{ab}{ao}$$

$$\therefore \text{Tan } An = \cos B \times \tan A$$

Control wheel.—A control wheel 35 is rotatably mounted on a wheel base 36 and driven thru a V belt drive by a variable voltage motor

45 37. Said motor is energized by a variable voltage generator mounted in the bed of the machine and adjusted by means of a rheostat, also in the bed, the handle of which is identified by numeral 40. Wheel 35 on base 36 may be adjusted angularly in a horizontal plane for grinding tapered surfaces or in a vertical plane for effecting an axial feeding movement of a work piece for thru feed grinding operation. Said control wheel may be adjusted toward and away from the grinding wheel for work pieces of various diameters. Said control wheel may also be moved axially either manually or by power. The means for effecting the above adjustments consists of a member 45 pivotally mounted at 46 and slidably 50 on bed 10 for angular adjustment thereon. The pivot member 46 is set in preloaded ball bearings 47 in order to provide a rigid mounting. Angular adjustment of member 45 is effected by means of screw 48 one end of which is rotatably mounted in the bed 10, the other end of which is threaded and inserted in a nut 49 in member 45. Integral 55 with member 45 is a cylinder 50 in which is slidably mounted a piston 51 having a piston rod 52 one end of which is threaded. Said threaded 60 end has a hollow hexagonal portion 54' into which a wrench may be inserted for rotating said piston rod. Said threaded end 53' fits a nut 53 which is secured to a slide member 55. A lock nut 54 serves to lock slide 55 in adjusted 65 position relative to piston 51.

Member 45 has formed thereon two upwardly facing bearing surfaces, 56 and 57, one V and one flat respectively. Member 55 has corresponding V and flat surfaces 60 and 61 respectively for engaging surfaces 56 and 57 on member 45.

Member 55 has a pair of upwardly facing guide surfaces extending transversely to those on the underside thereof. One of these guides 65 has a curved surface instead of the conventional V. The other guide 66 has a flat surface. A member 67 having a curved surface 68 for mating with guide 65 is secured to the underside of control wheel base 36 by means of screws 69.

The flat guide 66 has slidably mounted thereon a rectangular block 75 in which is inserted a hardened button 76. A vertical adjusting screw 77 threaded in a nut 78 in base 36 rests on said button. The upper end of said screw extends thru the top of base 36 and has a hollow hexagonal portion 79 into which a wrench may be inserted for turning same. A sleeve 80 on said screw is graduated in terms of angles to which the control wheel may be tilted. A clamp for said screw consists of a setscrew 81 having a beveled point 82. One end of a pin 83 engages the surface of screw shaft 77, the other end has a beveled point 84 in contact with point 82.

In Figure 11 is shown an alternate type of control wheel, said wheel 245 has ridges 246 and grooves 247 practically identical with those formed on the grinding wheel 15. For most thread grinding jobs a smooth faced control wheel is adequate and superior. However on some work such as that having a large diameter, the ridged surface is helpful in feeding and in maintaining proper control of rotation of a work piece. As with the plain surface control wheel, the axis of the grooved wheel must be tilted in accordance with the helix angle with respect to the axis of the work. The ridges of the control wheel assist in maintaining the proper axial relation between the screw threads of the work piece and the ridges of the grinding wheel 15. The endwise adjustment of wheel base 36 may be used to effect proper lateral relation between the ridges of the grinding wheel and those of the control wheel.

Feed mechanism—control wheel.—The means for adjusting the control wheel toward and from the grinding wheel consists of a feed screw 90 one end of which is threaded in a nut 91. Said nut is mounted on a bracket 92 which in turn is mounted on slide 55. The other end of said screw is supported in base 36 on spaced ball bearings 93 and 94. Between said bearings a worm wheel 85 is mounted on said screw shaft. A worm gear 86 on shaft 87 engages said worm wheel. A handwheel 88 on shaft 87 serves as a means for turning said shaft gears and screw for adjusting base 36 and control wheel 35 toward and from the grinding wheel 15.

Work rest.—The work supporting device consists of a base member 110 mounted directly on bed 10. Said base is slotted to receive a work supporting bar 111. Said bar has a work engaging surface inclined in the direction of the control wheel. Work pieces are held in position just before and after the grinding operation in the case of thru feed grinding by means of guides 112 pivotally mounted on the base 110 and urged toward the work by resilient means not shown.

Adjusting screws 122 serve to adjust bar 111 vertically to an angular position relative to the axis of the grinding or control wheels. For grinding screw threads, said bar must be tilted 75 15. Bracket 101 is secured to bracket 100 by

relative to the grinding wheel by an amount equal to the helix angle of the screw thread.

Dressing device for thread grinding wheel.—The dressing device for the grinding wheel consists of a bracket 100 attached to wheel base 11. A second bracket 101 is adjustably attached to bracket 100 by means of screws 109 for angular adjustment about pivot 124 on said bracket 100. Screwholes 109' are elongated to permit said adjustment. A self contained wheel dressing mechanism is inserted in a cylindrical portion 102 of bracket 101. Said mechanism includes a cylindrical housing 103 having a flanged portion 104 for resting on the cylindrical part 102 of bracket 101. A handle 104' on portion 104 serves as a means to effect angular adjustment of housing 103. A saw slot 145 in cylindrical portion 102 permits clamping of housing 103 in any adjusted position by means of screws 146. Slidably mounted in housing 103 is a tubular member 105 having a key way 106. A key 107 mounted in housing 103 projects into said keyway to permit sliding of member 105 but to prevent rotation thereof. The lower portion of member 105 supports a bracket 108. A wheel crushing tool 113 having annular ridges corresponding to the grooves in wheel 15 is rotatably mounted in bracket 108. Said crushing tool is driven at a relatively low speed by a motor 114 connected thereto thru a flexible connection 121 which permits vertical adjustment of said tool while the axis thereof remains parallel with that of the motor. While it is preferred to drive the wheel from the crusher, it is possible to drive the wheel direct while the crusher is driven. Wheel and crusher may also be driven in synchronism at the same pitch surface speed. Both control wheel 35 and crusher 113 are driven by adjustable speed motors. The same type of motor may be used for driving grinding wheel 15 as illustrated in Figure 13. The surface speed of the grinding wheel may be synchronized with that of the crusher by means of rheostat or by a mechanism such as that disclosed in Patents 2,302,304, granted November 17, 1942, and 2,287,449, granted June 23, 1942. Housing 103 may be angularly adjusted in cylinder 102 in order to place crusher 113 in proper alignment with wheel 15. Radial opening 118' in said housing permits insertion of a handle 104' for effecting said adjustment.

The means for adjusting said crushing tool toward and from the grinding wheel consists of a screw shaft 115 supported at one end in anti-friction bearings 116 in the upper portion 104 of housing 103. A portion of said screw shaft extends beyond said bearings and has a graduated disk 117 keyed thereto. Radial openings 118 in said disk permit the insertion of a handle 104' to turn same and hence the screw 115. A flanged sleeve 119 attached to one end of tubular member 105 is threaded internally to engage the threads of screw 115. In order to prevent back lash in said mechanism another internally threaded member 125 is slidably mounted in member 105. A pin 126 in member 105 extends into a slot 127 in member 125 to prevent rotation thereof. Said member 125 is held resiliently in spaced relation with sleeve 119 by means of a spring 128 thus preventing backlash between said threaded members. If necessary, bracket 101 may be adjusted in a vertical plane about pivot 124 by means of screw 129. The purpose of this adjustment is to assure parallelism between the axes of the crusher 113 and the grinding wheel 15. Bracket 101 is secured to bracket 100 by

means of screws 109. The screw holes 109' in bracket 100 are elongated to permit adjustment of bracket 101 relative to bracket 100.

Occasionally it is desirable to dress wheel 15 by passing a diamond dressing tool across the surface of said wheel. This may be done as shown in Figure 4 by mounting a diamond dressing tool in any suitable manner on control wheel base 36. Said dressing tool consists of a bracket 230 mounted on base 36 and having a diamond holding portion 231 extending into a position from which a diamond 232 can engage grinding wheel 15. Said base 36 may be shifted by means of hand wheel 88 and associated parts in order to position said diamond relative to wheel 15.

In order to form both the grinding wheel and the control wheel either simultaneously or separately with a single forming roller, a crushing tool 113 may be rotatably mounted in any suitable manner between the two abrasive wheels. Said crushing tool is driven by a motor 114 the speed of which is controlled by rheostat 95. The control wheel motor 37 and rheostat 152 have already been referred to. The grinding wheel 15 is driven by an adjustable speed motor 96 controlled by a rheostat 97.

Dressing device for control wheel.—The means for dressing the control wheel consists of a diamond holder in the form of a block 120 mounted on the rear of one of the guides 112. Said block has a diamond tool 123 removably mounted therein in position to engage the surface of control wheel 35.

Hydraulic features.—The hydraulic system consists of a motor 50 for providing the traverse movement of control wheel slide 55. Fluid under pressure is supplied by a pump 130 driven by motor 131. Flow of fluid in said system is held uniform by pressure operated relief valve 132 in conjunction with throttle valve 133, as described in copending application Ser. No. 524,948, filed March 3, 1944, which issued as Patent No. 2,419,940.

Said fluid under pressure passes from valve 133 thru line 135 and reversing valve 140. Said reversing valve directs fluid to one side or the other of cylinder 50 thru lines 136 and 137. The rate of flow thru said reversing valve is controlled by a throttle valve 134 which is built into valve 140.

Electrical equipment.—The electrical equipment on our machine is disclosed diagrammatically in Figure 14 and includes a grinding wheel motor 140, an oil pump motor 131, a generator drive motor 142, a coolant pump motor 143, a variable voltage generator 144 driven by motor 142 and a variable voltage motor 37 for driving control wheel 35 and supplied by said generator 144. This variable voltage drive is similar to that shown in Elberty application Patent No. 2,315,511, granted April 6, 1943, and consists essentially of a series generator 144 having series fields 150 and 151 and a rheostat 152 for varying the output of said generator. Such generator is connected to a series type motor 37 having a series field 155 and a resistor 156 which may be set for a predetermined motor speed, in this case a speed suitable for dressing the control wheel and which is substantially higher than the range of speeds used for grinding which are determined by the rheostat 152. Another variable voltage motor referred to previously drives forming roller 113.

Alternating current is supplied to motors 131, 140, 142 and 143 from lines 1, 2 and 3 thru suitable relays. Said relays are energized by cur-

rent at a lower voltage than that used on the motors. Said current is supplied from lines 1 and 3 thru a transformer 160 to lines 161 and 162. A master start switch 163 and a master stop switch 164 are inserted in line 161. Line 162 is a return line.

A selector switch 170 may be set to determine which motors should be in operation for each of the conditions of setting up, grinding, forming and dressing. The grinding wheel motor 140 is controlled by a relay 175 actuated by a coil 176. One contact 177 of said relay is connected to a normally open contact 178 in relay 179. Said relay controls oil pump motor 131 and is actuated by coil 180. A normally closed contact 181 in relay 179 includes the rheostat 152 in the variable voltage generator. Said rheostat is set for driving control wheel 35 at a predetermined speed for grinding. Contact 178 in relay 179 when closed completes a circuit which includes resistor 156 in the field circuit of control wheel motor 37. The purpose of this circuit is to drive said control wheel at a relatively high speed for dressing.

25 A third relay 185 having a coil 186 controls the generator driving motor 142 and coolant pump motor 143 which are connected in parallel. Lines 187 and 188 supply the primary of transformer 210. The transformer secondary 211 supplies rectifier 212 in the variable voltage drive circuit for control wheel 35.

30 Motor 114 for driving forming roller 113 is a variable voltage motor and is connected in parallel with control wheel drive motor 37. Said motors are controlled by a relay 220 actuated by a coil 221. In the normal position of the relay as shown contacts 222 are closed, to complete the circuit which includes control wheel motor 37. When coil 221 is energized contact 223 is closed and 222 opened. The control wheel motor 37 is thus stopped and forming tool motor 114 is started.

Operation

45 In order to start the machine, the operator presses master start button 163. This energizes coil 190 of relay 191 to close said relay and complete the circuit to selector switch 170. Said relay also establishes a holding circuit for coil 190.

50 *Set up.*—The first step in the operation of this invention is to set up, that is to arrange the various parts to machine a specific work piece. For this operation, the only motor which might be needed is the oil pump motor 131. By closing contact 176 of selector switch 170, current is directed thru line 200 to energize coil 180 of relay 179 which closes the circuit to oil pump motor 131. The control wheel 35 is adjusted toward grinding wheel 15 by turning hand wheel 88 until said wheel is in position for a work piece of the desired size. This is determined by adjusting wheel 35 until the work piece has moved up the inclined surface of bar 111 so that the center of the work is in the desired position relative to the plane of the axes of the two wheels 15 and 35. Work supporting bar 111 must be adjusted angularly relative to the grinding wheel axis by an amount equal to the helix angle of the threads on the piece to be ground so that the ridges 17 of wheel 15 will properly form threads on work piece 12. This adjustment may be accomplished by means of adjusting screws 122.

55 Control wheel base 36 must be tilted relative to the grinding wheel 15 to an angle equal substantially to double the helix angle. It may

be slightly more than double the helix angle. Tilting the control wheel 35 to double the helix angle has the effect of giving the work 12 the proper rate of axial feed per revolution for the helix angle of the thread being ground. This angle is fixed for any given screw. However, by changing the speed of the control wheel, the production rate of the machine may be changed. A slight additional tilt is effective to overcome friction between the work and work rest. This last is desirable but not essential.

If it is desired to grind a tapered work piece, wheel 35 may be so adjusted by turning screw 48 until the desired taper is indicated on a graduated plate 41 on member 45.

Wheel dressing.—In this machine the only operation resembling dressing which occurs at regular intervals during the grinding of a given size of thread is that of forming or crushing the grinding wheel 15. However it is sometimes desirable or necessary to dress the faces of both the grinding and control wheels. This is particularly true when new wheels have been placed on the machine or when the setup is changed for work of a different size.

For performing this dressing operation the operator turns selector switch 110 to the position marked dress. In this position circuits are closed at contacts 174, 174₁ and 174₂ to energize relays 175, 179 and 185 respectively. Relay 175 controls the grinding wheel motor 140. Relay 179 controls oil pump motor 131. Relay 185 controls generator drive motor 142 and coolant pump motor 143. When wheel motor relay 175 is energized, contactor 177 closes a circuit which includes contactor 178 of oil pump relay 179. Thus when relay 179 is energized the circuit thru contactor 178 is closed. This circuit includes resistor 156 in the field of control wheel motor 37. The effect of closing this circuit is to increase the speed of motor 37 and hence of control wheel 35 to a speed suitable for dressing. The operator turns hand wheel 88 to withdraw wheel 35 to a position in alignment with diamond 123. Valve 140 is then turned to direct fluid under pressure to one side of cylinder 50. Piston 51 then moves wheel support 36 and wheel 35 past diamond 123. Valve 140 is turned in the opposite direction to return said wheel to its original position. The rate of movement of said piston and wheel support is determined by throttle valve 134 which is built into valve 140. If it is desirable or necessary to dress grinding wheel 15, diamond 232 may be used. Said diamond is mounted on bracket 230 on wheel base 36. The traverse movement described above may be used to pass said diamond across wheel 15.

Because of the relative angular positions of the control wheel, the work rest and the plane of movement of wheel support 36 during a grinding operation, the matter of dressing said wheel along the path of travel of the work presents somewhat of a problem.

Assuming the grinding wheel 15 to be in a vertical plane, the work rest blade 111 will be inclined relative to the grinding wheel axis by an amount substantially equal to the helix angle of the thread to be ground. The control wheel 35 must be tilted relative to the work rest by an amount substantially equal to the helix angle and is thus tilted or inclined relative to the grinding wheel by an amount substantially equal to double the helix angle.

The elevation of the work 12 and hence the

point at which to begin dressing the control wheel 15 must be determined with all the parts in operative position. The center of the work should be above the center of the wheel 15 by an amount such that the axes of said wheel and the work will be in intersecting planes at the end of the grinding throat. The diamond may be adjusted to a gauge or simply to a mark made by rubbing the work against the surface of said wheel while at rest, said work rests on the work support bar after said bar has been adjusted to place the work in the desired position relative to the wheel centers.

The path of the work begins preferably above the center of the grinding wheel at the entrance to the throat and intersects the plane thru the grinding wheel axis as it leaves said throat. These conditions must be the same regardless of whether the grinding wheel is directly above the control wheel or in some other angular relation thereto. This provides a throat which becomes narrower as the work moves along its path. Generally the path of travel of the work relative to the grinding wheel may be described as follows. The path of travel of the work across the grinding wheel is a line *ab* intersecting the plane which contains the wheel axis and the point *b* where the work leaves the wheel, the angle of intersection being the helix angle of the screw thread to be ground. This is illustrated in Figures 16 and 17. Actually the line *a*—*b* is not a straight line because it follows the curvature of the wheel thru a short distance as it moves thru the grinding throat. However, the actual path is so nearly a straight line that it is difficult to see or show the difference on a small scale drawing.

From the above, it would be apparent that the method of producing finished screw threads on work pieces in a centerless grinder, whether the work pieces be unthreaded or whether they have pre-cut threads thereon, consists in providing a grinding wheel with annular ridges thereon, a control wheel and a work support having a smooth surface on which the work piece is free to move endwise, spacing the control wheel from the grinding wheel so as to provide a grinding throat, arranging the axes of the wheels in substantially parallel planes and inclined in opposite directions with respect to said work rest at an angle thereto substantially equal to the helix angle, positioning the work rest so that the grinding throat has a minimum width at the exit end thereof measured from the bottom of the grinding wheel grooves to the surface of the control wheel substantially equal to the diameter of the finished work piece, placing the work piece to be ground on the work rest and rotating and moving said work piece endwise through the throat solely by the action of the grinding wheel and control wheel operating through their frictional contact with the work piece.

During dressing, the control wheel moves in a horizontal direction. During grinding the work moves at an angle to the grinding wheel axis equal to the helix angle. The work also moves at the same angle to the control wheel which is double the helix angle from the grinding wheel axis. In order to dress along this path on the control wheel, said wheel must be tilted so that its axis is parallel to the surface of the work rest or to the axis of the work. The diamond is adjusted to the previously marked position referred to above and the control wheel

is passed across it making a path thereon which is spaced angularly from the axis of said wheel by the amount of the helix angle. After dressing, said wheel is tilted back to double the helix angle and the path of the diamond across the face thereof will be parallel to the axis of the work.

The third step in preparation for a grinding operation is to form the grinding wheel 15. This is done by a method known as crushing. Selector switch 170 is turned to the forming position. In this position contacts 172 and 172₁ are closed. Contact 172 is in the circuit to generator motor relay 185. Contact 172₁ is in the circuit to relay 220. When energized, said relay opens the circuit to control wheel motor 37 and closes the circuit to crusher motor 114. Oil pump motor 131 is not in operation at this time and therefore normally closed contactor 181 in relay 179 completes a circuit which includes rheostat 152 in generator field 150. This rheostat controls the grinding or slow speed of the motor 37 and therefore of crusher motor 114 also.

Crusher roller 113 may be fed toward grinding wheel 15 any predetermined amount as indicated on disk 117. Said disk may be rotated by means of a handle inserted in radial holes 118. Said disk is keyed to screw 115. When said screw is turned, member 165 and forming roller 113 move toward or away from the grinding wheel 15. Rotation of roller 113 causes rotation of wheel 15, the result of this rolling together being that the forming tool produces its contour on the grinding tool 15. If particles of dirt or grit lodge in the grooves of roller 113 an inaccurate thread may be formed. In order to prevent this, a brush 240 mounted in the fender portion of base 11 engages said grooved surface and removes all particles therefrom.

After wheel 15 has been formed, switch 170 is turned to the grinding position. In this position contact 173 is closed to start the grinding wheel motor 140. Contact 173 is also closed. This contact is connected to contact 172 which controls the generator motor 142 to drive control wheel motor 37. Work pieces are introduced into the grinding throat. Sometimes the work tends to rise from the rest due to the action of the control wheel. This may be overcome by any suitable hold down device.

As soon as a work piece 12 is introduced into the grinding throat, the action of the grinding wheel 15 urges said work piece against the control wheel. The control wheel 35 then rotates the work; and, because of the angular relation of said control wheel with the smooth work rest 12, it not only rotates the work piece, but moves it endwise at a rate of one or more full threads per revolution. The control wheel 35 provides the sole feeding means of the work piece through the grinding throat; and in the case of a prethreaded work piece, this rate of feed prevents the ridged grinding wheel from functioning as a nut, and thus the ridges on the grinding wheel serve neither to advance nor to retard the endwise movement of the work piece. If the feeding action of the control wheel is too great, the leading flanks of the threads will be ground too heavy. If the feeding action of the control wheel is too little, the work piece will have to provide a part of the endwise movement by its threading action with the ridges of the grinding wheel; and the trailing flanks of the thread will be ground too heavy. In

either case, the result is an inaccuracy in lead. With the control wheel set at the helix angle of the screw to be ground, relative to the work rest, the rate of feed of the work is independent of any threading action between the work and the ridges of the grinding wheel; and maximum lead accuracy is attained.

We claim:

1. The method of generating screw threads of a predetermined helix angle on a substantially cylindrical workpiece in a centerless grinding machine having a grinding wheel with annular ridges thereon, a control wheel peripherally opposed to said grinding wheel and spaced therefrom to form a grinding throat, and a smooth surface work rest for supporting the workpiece for movement between the opposed portions of said wheels, which consists in arranging the axes of said wheels in substantially parallel planes and inclined in opposite directions with respect to said work rest at an angle thereto substantially equal to said helix angle, and with the peripheral faces of said wheels spaced from each other to provide a grinding throat having a minimum width measured from the bottom of the grinding wheel grooves to the surface of the control wheel substantially equal to the diameter of the workpiece, supporting a cylindrical workpiece on the work rest with its axis maintained parallel with the smooth surface thereof, rotating the workpiece solely by the driving and controlling effect of the grinding and control wheels and simultaneously moving the workpiece endwise through the throat in predetermined timed relation with the rotation solely by the action of the grinding and control wheels operating through their frictional contact with the workpiece.

2. The method of producing finished screw threads on work pieces of a predetermined helix angle in a centerless grinding machine having a grinding wheel with annular ridges thereon, a control wheel peripherally opposed to the grinding wheel and spaced therefrom to form a grinding throat, and a smooth surface work rest for supporting the work piece for movement between the opposed portions of said wheels, which consists in arranging the axes of the wheels in substantially parallel planes, and inclined in opposite direction with respect to the work rest at an angle thereto substantially equal to the helix angle, said work rest being positioned relative to the axis of the grinding wheel so as to provide a grinding throat which is progressively narrower from the entrance end to the exit end thereof, the width at its exit end being substantially equal to the diameter of the finished workpiece, supporting a workpiece on the work rest and rotating the workpiece solely by the driving and controlling effect of the grinding and control wheels for simultaneously moving the workpiece endwise into and through the grinding throat in predetermined timed relation with the rotation solely by the action of the grinding and control wheels operating in frictional contact with the workpiece.

3. A centerless grinding machine for producing finished screw threads of a predetermined helix angle on workpieces comprising a grinding wheel having annular ridges thereon, means for rotating said grinding wheel, a control wheel peripherally opposed to said grinding wheel and spaced therefrom to form a grinding throat, means for rotating said control wheel, a smooth

surface work rest for supporting a workpiece for free endwise movement through said grinding throat, said work rest being inclined relative to the axis of the grinding wheel at an angle substantially equal to the helix angle of the screw to be produced so that a thread will be formed having a shape substantially conforming to said annular ridges of the grinding wheel, the axis of said control wheel being inclined in the same direction as the work rest and at an angle thereto substantially equal to the helix angle of the screw so that a workpiece will be fed solely by the control wheel endwise along said smooth work rest at a rate of one or more full threads per revolution to produce a finished thread on the workpiece of the desired predetermined helix angle.
